CONVERTIBLE TOP HEADER LOCKING MECHANISM

John W. Votypka, Detroit, Mich., and Clifford E. Hale, Denver, Colo., assignors to Detroit Harvester Company, Detroit, Mich., a corporation of Michigan

Application September 10, 1951, Serial No. 245,953

6 Claims. (Cl. 296—120)

The present invention relates to header locking mechanism, and more particularly to mechanism for effecting a centering and locking action between the front header bar of a convertible top of a vehicle and the header bar at the top of the windshield.

The present invention is a continuation-in-part of our prior copending application, Serial No. 92,204 filed May 9, 1949, now abandoned.

It is an object of the present invention to provide locking mechanism of the character described capable of compressing rubber seals conventionally provided intermediate the top of the windshield header bars and withstanding considerable vibration.

It is a further object of the present invention to provide locking mechanism of the type described, pleasing in appearance so far as it is visible, and in which the operating handle is placed both for ready accessibility and in a position so that when the parts are in locking engagement, the handle is in alignment with the header bars, and preferably located in underlying relation to the top header bar.

It is a further object of the present invention to provide locking mechanism for convertible tops including elongated lock actuators adapted to be in tension when the locking mechanism is moved toward locking position, in conjunction with an operating handle disposed to assume a position substantially parallel to the header bars when the locking mechanism is engaged, whereby the operating handle serves as an infallible indication that the lock mechanism is in actual engagement.

It is a further object of the present invention to provide locking mechanism for convertible top structure comprising locking levers adjacent the ends of the header bars, slotted pins associated with the levers, the slots in the pins and the levers being formed to provide an initial centering cam action in addition to a clamping action urging the header bars into engagement with each other.

It is a further object of the present invention to provide locking mechanism designed to provide relatively great mechanism advantage so that an operating handle may bring about a firm and secure locking engagement with a minimum of movement.

It is a further object of the present invention to provide locking mechanism of the character described in which manufacturing economy is realized through a minimum number of parts and through relatively great acceptable manufacturing tolerances.

Other objects and features of the invention will become apparent as the description proceeds, especially when taken in conjunction with the accompanying drawings in which:

Figure 1 is a fragmentary plan view partly in section, of the improved locking mechanism, taken substantially on the line 1—1, Figure 3.

Figure 2 is a fragmentary front elevational view of the locking mechanism with parts broken away for clarity.

Figure 3 is an enlarged fragmentary sectional view on the line 3—3, Figure 1.

2

Figure 4 is a fragmentary sectional view on the line 4—4, Figure 3.

Figure 5 is a fragmentary sectional view on the line 5—5, Figure 1.

5 Figure 6 is an enlarged plan view of a combined locking and actuating member employed in the mechanism.

Figure 7 is a rear elevational view of the member shown in Figure 6.

10 Figure 8 is a side elevation of the member shown in Figure 6.

Figure 9 is a fragmentary sectional view through a locking pin showing a centering camming arrangement between the pin and locking lever.

15 Figure 10 is a fragmentary sectional view on the line 10—10, Figure 9.

Figure 11 is a view similar to Figure 9 showing a modified construction of camming arrangement.

Referring now to the drawings, the invention is directed 20 primarily to locking mechanism for securing a top header bar 10 of a convertible folding top to a windshield header bar 12, which as appears in Figure 3 extends longitudinally across the front of the vehicle above the windshield 14. In order to prevent the entrance of moisture into the interior of the vehicle when the top is in place, suitable sealing means are provided intermediate the top header bar and the windshield header bar. In Figure 3 this sealing means is illustrated in the form of a gasket 16 secured to an upstanding flange 18 extending along the rearward edge of the windshield header bar and 30 engageable with a portion of the under-surface of the top header bar 10.

Several problems have to be successfully solved in order 35 to produce a satisfactory lock between the windshield header bar and the top header bar. In the first place it is of course of first importance to provide means which will secure the top in positive manner against dislodgment due to vibration and air pressure due to forward velocity of the motor vehicle. Also, in order to insure an adequate seal between the two header bars it is essential 40 that the top header bar be properly oriented with respect to the windshield header bar prior to completion of clamping movement urging the two bars together. Finally, it is of primary importance to provide a lock which is positive in operation and which includes visible 45 indications showing whether the top is locked in open position. In the past serious accidents have occurred as a result of the convertible top becoming loose in use and blowing upwardly and rearwardly with considerable violence due to the very great air pressure resulting from rapid forward motion of the vehicle.

The top header bar comprises a pair of upstanding posts 50 located adjacent the ends of the windshield header bar, and an intermediate upstanding post 22. The top header bar 10, at the forward end of the convertible top, has 55 corresponding openings 24 and 25 through which the upstanding posts 20 and 22 respectively extend. Each of the posts, as best seen in Figures 4 and 10, is provided with an inclined transversely extending slot 26 for a purpose to be later described.

60 Located within the interior of the top header bar 10 and adjacent each of the end openings 24 therein, is a camming and locking lever 28 which is pivoted for rocking movement about a vertical axis established by a pivot pin 30. The levers 28 are preferably in the form of bell 65 crank levers each having a camming and locking arm 32 and an actuating arm 34. The camming and locking arm 32 is arranged to enter into the inclined slot 26 in the adjacent pin and for this purpose the outer end portion of the camming and locking arm 32 is preferably inclined 70 in conformity to the inclination of the slot 26, and in addition, is preferably given a transverse camber as well illustrated in Figures 4 and 10.

Adjacent the center opening 25 and within the hollow top header bar 10 is provided an actuating and locking device indicated generally by the reference numeral 36, the details of construction of which are best illustrated in Figures 6-8. As seen in these figures, the actuating and locking device 36 is of general U-shaped cross-section comprising a relatively short leg 38, a relatively longer leg 39, and a connecting web 40. A pivot pin 42 is welded or otherwise permanently secured to the device for actuating the same and is provided with a reduced extension 44 having a pin receiving opening 46. In use, the pivot pin 42 passes through a bearing 48 which is located in an opening in the bottom wall of the top header bar 10, as seen in Figure 3. Secured to the reduced portion 44 is an actuating handle 50 which by means of a connecting pin 52 is directly connected to the device 36.

The relatively short leg 38 is offset laterally to comprise an actuating lever arm 52 and carries a pivot pin 54 rigidly secured thereto. The relatively longer leg 39, as best seen in Figure 6, includes a lateral extension 56 which constitutes a second actuating lever arm and carries a pivot pin 58. The outer end of the leg 39 constitutes the locking portion of the device and includes an inclined portion 60 shaped to cooperate with the inclined slot provided in the center locking pin 22.

The specific mounting of the actuating device 36 is best illustrated in Figures 3 and 5. Located centrally of the top header bar is a supporting plate 61 which is riveted, welded, or otherwise secured to the upper surface of the bottom wall of the top header bar 10. The plate 61 is provided with a central opening therethrough in which is received the collar 62 of the bearing 48. In order to prevent rotation of the bearing 48 in the plate 61, the plate is staked as indicated at 63 in Figure 5, and the projecting element formed thereby extends into a peripheral recess 64 formed in the bearing 48. Plate 61 also has a stop 61a limiting rotation of device 36 in unlocking direction.

Means are provided interconnecting the camming and locking bell crank levers 32 and the actuating and locking device 36. As best seen in Figures 1 and 2, this means takes the form of an elongated link 65 having a flattened portion 66 pivotally connected to the pin 58 extending upwardly from the lever arm 56. At its outer end the link 65 has a flattened portion 67 pivotally connected to a pivot pin 68 provided at the outer end of the actuating lever arm 34 of the bell crank lever 28. In like manner, a second elongated link 70 is provided connecting the actuating lever arm 34 of the other bell crank lever 28 to the pivot pin 54 extending upwardly from the actuating lever arm 52 of the device 36.

The arrangement is such that as the operating handle 50 is moved to locked position, thereby swinging the inclined locking portion 60 of the device 36 into engagement in the slot of the pin 22 at the center of the header bar, bell crank levers 28 are simultaneously rocked to cause their camming and locking arms 32 to enter the inclined slots provided in the pins 20.

One of the important features of the present invention is that the links 70, the levers 28, and the actuating device 36 are so related that as the bell crank levers 28 are swung toward and into locking position links 65 and 70 are in tension. Accordingly, since the material of the links 65 and 70 is not extensible, it is impossible to swing the handle to a position corresponding to fully locked position unless both of the levers 28 actually result in locking engagement with the corresponding pins. This is to be contrasted with an arrangement in which the links 65 and 70 might be connected to operate in compression to effect locking engagement. In such case, if the locking levers fail to engage in the slots in the pins, continued movement of the handle 50 would be permitted and would merely result in bowing the actuating links. However, in the present case, unless

the locking portions of the lever arms 28 actually enter into the slots in the pins so as to effect a secure locking of the top header bar, it is impossible to swing the handle 50 to locked position.

It is further to be noted that when the locking levers 28 are in locked position, the handle 50 extends generally parallel to the header bars. Since its connection to the actuating device 36 is through the bottom wall of the top header bar, this means that the operating handle 50 is in position directly beneath the top header bar. This is important for two reasons: In the first place, the free end of the operating handle 50 in operating position is thus protected by its position beneath the top header bar so that it constitutes no hazard to the occupants of the vehicle in the case of an accident. In the second place when the top header bar is roughly in position overlying the windshield header bar, the fact that the handle 50 is in its illustrated position parallel to the header bars is a positive and reliable indication that the top header bar is securely retained in position by the locking means. As previously indicated, this is a safety feature of considerable importance since it avoids the possibility of the occupants of the car moving the operating handle to a position in which the top header bar is normally locked, but without in fact effecting positive locking thereof.

Reference was previously made to the function of the apparatus illustrated herein to properly center the top header bar relative to the windshield header bar prior to urging the two header bars into tight engagement with each other. Mechanism for this purpose is best illustrated in Figures 9-11, to which reference is now made. In these figures one of the camming and locking levers 28 is illustrated in detail in its association with the locking pin 30. As seen in these figures it will be observed that the camming and locking arm 32 of the lever 28 has an end surface 80 which is shaped to cooperate with the bottom wall or surface 82 of the groove 84 such that swinging movement of the lever 28 in a counter-clockwise direction, as seen in Figure 9, will cam the top header bar longitudinally of itself if it is in misalignment with respect to the windshield header bar transversely of the vehicle.

Obviously, the lever shown in Figure 9 acts in conjunction with the corresponding lever at the opposite end of the header bar so that in the event of misalignment between the header bars transversely of the vehicle, one or the other will be effective to cam the top header bar into proper position. Moreover, it will be observed that the inclination of the bottom wall 82 of the slot and the post extends at an angle of roughly 45 degrees with respect to the longitudinal axis of the vehicle so that the levers are also effective to cam the top header bar longitudinally into its correct mating relation with the windshield header bar.

In the arrangement illustrated in Figure 9 it will be apparent that the camming action of the arm 32 against the bottom wall 82 of the slot is concentrated at the corner 86 thereof and that full camming of the header bar 60 to proper registering position is not effected until the lever arm reaches the position shown in Figure 9.

In Figure 11 there is illustrated a modified arrangement in which the bottom wall of the slot in the post 20 includes a camming portion 90 and a second portion 92 which is arcuate and concentric with the pivot axis of the pivot pin 30. In this case centering of the top header bar is accomplished when the corner 94 of the camming and locking arm 32 reaches the junction between the surfaces 90 and 92. Thereafter, further rocking motion 70 of the lever 28 to the fully locked position illustrated results in downward clamping of the top header bar against the upper surface of the bottom header bar (or more specifically, against the sealing member 16). In other words, a sequential action results from the operation of the lever arm illustrated in Figure 11. During the initial en-

gagement between the camming and locking arm and the surface 90, a camming action takes place which results in centering and properly locating the top header bar with reference to the windshield header bar. Thereafter, further rocking motion of the lever 28 results in downward motion of the top header bar into sealing engagement with the windshield header bar. Of course, some downward movement of the top header bar takes place during interengagement between the camming and locking arm 32 and the camming surface 90 of the slot, but the parts will be arranged such that final clamping engagement between the top and windshield header bars is not effected until after completion of the camming of the top header bar into proper registration with the windshield header bar.

The drawings and the foregoing specification constitute a description of the improved header locking mechanism in such full, clear, concise and exact terms as to enable any person skilled in the art to practice the invention, the scope of which is indicated by the appended claims.

What we claim as our invention is:

1. In a header for convertible tops, locking mechanism for fastening the header to the vehicle body, thereby to maintain the top in closed position comprising, a U-shaped combination locking and actuating member mounted centrally of said header for pivotal movement on an axis that is substantially vertical when the top is in closed position with the legs of the U overlying one another, a handle having a relatively long lever portion operably associated with said member and adapted for swinging movement in a substantially horizontal plane for moving said member between locked and unlocked positions, right and left bell cranks pivotally mounted in opposite sides of said header, one leg of said U-shaped member and one arm of each of said bell cranks being respectively adapted for engagement with posts on the vehicle body, a link connecting one leg of said U-shaped member with one of said bell cranks, a second link connecting the other leg of said U-shaped member with the other bell crank whereby movement of said handle toward locking position simultaneously actuates said member and, through tension movement of said links, said bell cranks into locking engagement with said posts.

2. Mechanism as defined in claim 1 in which said posts are provided with inclined slots and said bell cranks have first arms connected to said links, and second arms constituting the portions entering said slots, the said second arms of said levers disposed to extend obliquely with respect to the length of said top header bar when in locking position, the bottom walls of said slots and the ends of said second arms being relatively inclined to center said top header bar on said windshield header bar.
  - 5 10 3. Mechanism as defined in claim 2 in which the bottom walls of said slots and the ends of said second arms are shaped to complete centering of the top header bar prior to engagement thereof with said windshield header bar.
  - 15 4. Mechanism as defined in claim 3 in which the bottom walls of said slots and the ends of said second arms include concentric surface portions effective to retain said top header bar in centered relation during additional swinging movement of said levers following centering 20 movement thereof.
  - 25 5. Mechanism as defined in claim 1, in which each of said posts is provided with a slot and each of said bell cranks includes an edge portion engageable with the inner wall of the slot in the adjacent post, thereby to center said top header bar prior to final clamping against said windshield header bar.
  - 30 6. Mechanism as defined in claim 5, in which the portions of said bell cranks entering said slots have a component of motion transversely of said top header bar, 25 and include lateral surfaces engaging the bottoms of said slots with a camming action, thereby to center said top header bar longitudinally thereof with respect to said windshield header bar.
